Inventor:

FREDERICK HACHMANN,

UNITED STATES PATENT OFFICE.

FREDERICK HACHMANN, OF ST. LOUIS, MISSOURI, ASSIGNOR OF ONE-FOURTH TO JAMES B. HOLLIS AND ONE-FOURTH TO FRED C. SCHOENTHALER, BOTH OF ST. LOUIS, MISSOURI.

FURNITURE-TIP.

1,217,091.

Specification of Letters Patent. Patented Feb. 20, 1917.

Application filed March 13, 1915. Serial No. 14,276.

To all whom it may concern:

Be it known that I, FREDERICK HACHMANN, a citizen of the United States, and residing at St. Louis, in the State of Missouri, have invented a certain new and useful Improvement in Furniture-Tips, of which the following is a specification.

This invention relates to tips, and more particularly, to tips for furniture, such as 10 chairs and the like.

One of the forms of furniture tips now on the market has prongs formed integral with the head forming the tip. Unless such a tip is made of heavy metal, it will dent when 15 it is hammered on the tipped article. When, however, this tip is made of heavy metal, the prongs will, of course, be heavy, and this is liable to cause the tipped article to split. Moreover, such integral construction 20 has the disadvantage in that the desired glass hardening of the head will cause the prongs to be brittle and, therefore, easily broken. It has been proposed to construct a furniture tip of separate parts forming 25 an integral structure, but such a device is not only complicated and expensive, but is also difficult to attach, and, moreover, rattles when in place.

One of the objects of this invention, therefore, is to construct a furniture tip comprising a base adapted for attachment and a head which interlocks with the base to form the extreme tip.

Another object is to provide a tip which is 35 simple in construction, consists of a few parts, is easily applied, will not split the tipped article, and which is cheap to manufacture.

Further objects will appear from the 40 detailed description taken in connection with the accompanying drawings, in which:

Figure 1 is a side elevation of an article, such as a furniture leg, which is tipped with a device embodying this invention;

Fig. 2 is a section on the line 2--2, Fig. 1;

Fig. 3 is an inverted perspective view of Fig. 1, but with the head removed;

Fig. 4 is a perspective view of the base;

Fig. 5 is a perspective view of the head; 50 and,

Fig. 6 is an enlarged section of Fig. 2.

Referring to the accompanying drawing, 10 designates the base, which is in the form of a flanged or cup-shaped disk having a

flange 11, which flares outwardly as more 55 particularly shown in Fig. 6. This base has a central perforation 12, and also a pair of prongs 13 struck up from the body of the base and adapted to take into the article 9 to be tipped. The perforation is adapted 60 to receive a suitable fastening, such as a screw 14. The head 15 comprises a cup-shaped structure having the lower face thereof in the form of a segment of a sphere, and having a flange 16 provided with a plurality of inwardly struck up parts 17 forming 65 a bead. The inner faces of these struck up parts, when formed by striking up the middle, are slightly beveled to merge into the beaded flange, as shown in Fig. 6. Preferably these struck up parts are positioned 70 at diametrically opposite points.

In order to apply the device to an article to be tipped, the base is preliminarily positioned and preliminarily secured in position by the insertion into the article to be tipped of the prongs 13. The screw 14 is then inserted through the hole to firmly secure the base in place. The head 15 is now pressed over the flange 11 of the base, and 80 this causes the flanges 11 and 16 to yield slightly at the engaged points, the flange 11 inwardly and the flange 16 outwardly, thereby causing the bead to snap over the flange and take over the same. This firmly 85 secures the head in position on the base, thereby forming a complete tip.

The parts are made of sheet metal formed by suitable dies, and can, therefore, be constructed very cheaply. By making the tip 90 of two separate parts it can be attached by a central fastener such as a screw, so as to firmly secure the base in position. Since the parts can be made interchangeable, the wearing out part, namely, the head 15, can 95 be readily replaced. The base can be made of cheap and thin metal, while the head can be made of a heavier metal, and this head can be hardened so as to resist wear. The short prongs 13 provide a convenient 100 means for preliminarily locating and positioning the device on the tipped article for the more permanent attachment by the central screw. The flared construction of the flange not only makes this flange resilient, 105 but also provides a ledge which firmly holds the head in position on the base. The arrangement of the bead parts at opposite

points furnishes a resilient construction permitting the ready engagement of the parts.

It is obvious that various changes may be made in the details of construction without departing from the spirit of this invention. It is, therefore, to be understood that this invention is not to be limited to the specific construction shown and described.

Having thus described the invention what is claimed is:

- 10 1. A furniture glide comprising a cupped pressed metal base adapted for attachment to the leg of an article of furniture, and a pressed metal head designed to coöperate with said base to form the active floor engaging surface of said glide, said base and head being relatively yieldable transversely and constructed and arranged to form a downturned flange and a lug adapted to snap into coöperative interlocking engagement with said flange for detachably secur-

ing the head on the base and permitting ready disengagement of the head at will.

2. A furniture glide comprising a shankless, cupped pressed metal base having a 25 downturned flange and adapted for attachment to the leg of an article of furniture by means of an extraneous fastener, and a pressed metal head yieldable relative to said base and having means constructed and arranged to snap into detachable interlocking frictional engagement with said flange for permitting ready disengagement of said head at will, said head forming the active 30 floor engaging surface of the glide. 35

In testimony whereof I affix my signature in the presence of these two witnesses.

FREDERICK HACHMANN.
